UNITED STATES PATENT OFFICE.

PAUL KAMINSKI, OF BERLIN-PANKOW, GERMANY, ASSIGNOR TO SIEMENS & HALSKE, AKTIENGESELLSCHAFT, OF SIEMENSSTADT NEAR BERLIN, GERMANY, A CORPORATION OF GERMANY.

GUN-LAYING APPARATUS.

Application filed October 26, 1923. Serial No. 670,884.

To all whom it may concern:

Be it known that I, PAUL KAMINSKI, a citizen of the German Empire, residing at Berlin-Pankow, Germany, have invented 5 certain new and useful Improvements in Gun-Laying Apparatus, of which the following is a specification.

This invention relates to gun laying apparatus and more particularly to apparatus 10 for adjusting the elevation of several pieces of ordnance simultaneously from an observation point by means of remote electric control.

In the known remote controlling devices 15 for guns all guns of a battery receive as a rule the same range communicated from the transmitter at the central station or from the directing-gun. Owing to the varying distance of the guns from the range transmitter 20 or from the directing-gun the impact of the projectiles thus varies in correspondence with these varying distances. To correct this error special correction tables or conversion apparatus were employed at each individual gun. This proceeding caused loss 25 of time and mistakes.

The object of the present invention is to avoid these drawbacks and to eliminate the 30 human factor by combining an automatic correcting device with each gun or with the range transmitting apparatus.

In the drawings:

Fig. 1 is a diagram of the principle underlying the invention.

Fig. 2 is the application of the improved apparatus to the elevating device of the gun.

Fig. 3 is the application of the improved apparatus to the tangent sight of the gun and

Fig. 4 on the directing telescope of the gun. Similar parts are indicated by the same reference signs throughout all the figures of the drawings.

The principle of the invention will first be 45 pointed out by reference to Fig. 1. Along the base-line 0—180 are disposed the pieces of ordnance I—IV and the transmitter G. The target is assumed to be at 60. The distances of the target from the guns and the 50 transmitter are indicated by E with the corresponding index, the angles between the line from the directing-gun to target and the base-line, the so-called lateral direction position, is indicated by α and the cor-

responding index and the distances of the 55 guns from the transmitter by a and the corresponding index. As the distance of the guns from one another is very small compared with the distance of the target, it may be assumed that 60

$$E_4 = E_g + a_4 \cos \alpha$$

At $\alpha = 0^\circ$ or 180° $E_4 = E_g \pm a_4$, at $\alpha = 90^\circ$ E_4 may be made $= E_g$ with sufficient accuracy.

It is therefore required to correct the 65 linear value a multiplied by the cosine of the lateral direction α .

In the Figures 2—4 various devices are 70 shown, which effect this correction automatically.

Referring to Fig. 2, which shows the improvement applied to the elevating apparatus of the gun, the pointers z_1 and z_2 of the coarse and fine receivers of the receiver plant B are electrically controlled from a directing telescope. The gun is elevated in likewise known manner by means of the crankhandle H_1 across s_2, s_1, t and the levelling quadrant L and simultaneously the counter pointers z_3 and z_4 are by the gearing 75 3 to 9 made to follow the remotely controlled pointers z_1 and z_2 . During this rotation the drum k furnished with a spiral groove is 80 rotated by the wheels 11, 12, 13, 14. The drum k acts as so-called sine link. It is 85 journaled in a rotatable bow b , which is operated by the lateral direction levelling wheel H_2 across 19 in correspondence with the lateral angle α . The spiral groove in 90 the drum k is gauged in accordance with the angle of elevation corresponding with the distance. Preferably similar drums are employed for all guns and the varying distance of the guns is provided for by different ratios of transmission, for instance in the 95 wheels 16, 17. The groove of the drum k is engaged by a pin n . The pin n slides along a spindle o , which is journaled in the rotatable bow b . The pin n engages with its other end a slot 1 of a link, one beam st 100 of which is provided with a rack. This link is so arranged within the casing of the apparatus, that it can only slide in the direction of the beam provided with the rack. By this rack the motion is transmitted to the planet 105 wheel 7 across the wheels 15, 16, 17, 18 and thereby to the counter pointers z_3 and z_4 .

Referring to Fig. 3 which shows the im-

proved apparatus applied to the tangent-sight of the gun and not to the gun itself, it will be seen, that the counter pointers z_3 and z_4 are made to follow the remotely controlled pointers z_1 and z_2 of the receiver plant across the intermediate members 3-9 by turning the tangent-sight adjusting wheel H_3 . The wheel H_3 moves simultaneously across s_3 the toothed quadrant L_1 10 of the telescope support F. Across the intermediate members 11-14 the drum k is rotated again, which in its turn acts again upon the planet wheel 7 by means of the parts $n, st, 15$ to 18. The lateral direction 15 adjusted by the handwheel H_2 across 20, 21, 22 is transmitted by the toothed rim 23, pinion 24, articulated shaft 25 and gearing 19 to the bow b.

Preferably the correcting members for the 20 constructions illustrated in Figs. 2 and 3 are housed within the receiver casing. The drum k is adapted to be easily exchanged in accordance with the various charges of the gun (for instance fight-practice-aiming 25 charge).

Fig. 4 shows a diagrammatic representation of the application of the correcting device at the transmitter, so that the guns receive right away the range corrected in accordance with their position. By means of the crank-handle 30, which may be replaced by any suitable power drive, the transmitter 30 distance is adjusted upon the scale 31. Hereby the coarse transmitting system G 35 common to all guns is adjusted across the elements 32, 33 and 34. Simultaneously the shaft 33 revolves across 35, 36 the planet 40 wheels 37 of the fine transmitters F_1-F_4 belonging to each individual gun. When 45 adjusting the crank 30 the drum k is turned by the parts 11, 12, 13 and 14, which transmits its motion across $n, st, 15, 40, 16, 17, 18$ and planet wheel 37 to the fine transmitting system F_1-F_4 . The blow is in this construction rotated by the adjustment of the lateral direction upon the scale 38 by means of the crank 39 across the worm gear 40. The lateral direction may, however, also be 50 taken directly from the directing telescope of the transmitter plant. The different distance of the guns is preferably provided for by the ratio of transmission of the wheels 17.

It will be readily understood that the invention is by no means limited to the illustrated subdivision for coarse and fine systems and the follow-pointer plant may 55 equally well be replaced by direct remote control.

What I claim as my invention and desire 60 to secure by Letters Patent is:

1. In an arrangement for the telecontrol of the elevation of simultaneously levelled guns the combination of an electrical transmission system having transmitters placed 65 at a remote control station and receivers ar-

ranged near the guns and adapted to transmit a predetermined elevation angle, a mechanical device comprising a plurality of different coacting elements for correcting the elevation angle, mechanical means for operating one of said co-acting elements according to the lateral training angle of the guns, means for rotating a second element of said device in correspondence with the predetermined elevation angle and means for modifying the correcting movements of said co-acting elements with regard to the different distances between the remote control station and the individual guns. .

2. In an arrangement for the telecontrol of the elevation of simultaneously levelled guns the combination of an electrical transmission system having transmitters placed at a remote control station and receivers arranged near the guns and adapted to transmit a predetermined elevation angle, a mechanical device for correcting the elevation angle comprising a yoke, a drum having a spiral groove and being rotatably mounted in the yoke, and a pin, adapted to slide in the groove of the drum, mechanical means for turning said yoke according to the lateral training angle of the guns, means for rotating said drum in correspondence with the predetermined elevation angle, a set of gears each gear having a different ratio for modifying the correction value obtained by said mechanical device with regard to the different distances between the remote control station and the individual guns and means for mechanically connecting said set of gears to said pin.

3. In an arrangement for the telecontrol of the elevation of simultaneously levelled guns the combination of an electrical system having transmitters placed at a remote control station and receivers arranged near the guns and adapted to transmit a predetermined elevation angle, a mechanical device for correcting the elevation angle comprising a yoke, a drum having a spiral groove and being rotatably mounted in the yoke, and a pin, adapted to slide in the groove of the drum, mechanical means for turning said yoke according to the lateral training angle of the guns, means for rotating said drum in correspondence with the predetermined elevation angle, a set of gears each gear having a different ratio for modifying the correction value obtained by said mechanical correcting device with regard to the different distances between the remote control station and the individual guns, mechanical connection between said set of gears and said pin, planet gearings interposed between said electrical system and said correction device, one driving wheel of each planet gearing adapted to be turned in correspondence with the ratio of the pertaining modifying gear, and means for op-

erating the other driving wheel of each planet gear directly from the electrical system which transmits the predetermined uncorrected elevation angle.

5 4. In an arrangement for the telecontrol of the elevation of simultaneously levelled guns the combination of an electrical system having one coarse transmitter and a plurality of fine transmitters one for each 10 of the guns for transmitting a predetermined elevation angle, all of said transmitters being located at a remote control station, corresponding receivers located near the guns and being electrically connected 15 with said transmitter, a mechanical device, comprising a yoke, a drum having a spiral groove and being rotatably mounted in said yoke and a pin adapted to slide in said spiral groove, means for shifting the yoke of said

device according to the lateral training angle of the guns, a plurality of planet gearings, each adapted to adjust one of the fine transmitters of said system, means adapted to rotate said drum and to simultaneously adjust the coarse transmitter of said system 25 and to rotate one of the driving wheels of each of said planet gearing according to the value of the predetermined elevation angle and means for mechanically connecting the other wheel of each of said planet gearings 30 to the pin of said device, to modify the predetermined angle adjustments of the individual fine transmitters in accordance with the distance between the remote control station and the individual guns. 35

In testimony whereof I affix my signature.

PAUL KAMINSKI.
